(57) **CLAIM**

The ornamental design for an ergonomic handle, as shown and described.

DESCRIPTION

FIG. 1 is a top perspective view of an ergonomic handle according to the present design;

FIG. 2 is a right-side elevational view thereof shown in use

FIG. 3 is a left-side elevational view thereof shown in use

FIG. 4 is a bottom plan view thereof;

FIG. 5 is a top plan view thereof;

FIG. 6 is a back-side view thereof; and,

FIG. 7 is a front-side elevational view thereof.

The broken lines shown represent the user interaction with the ergonomic handle and form no part of the claimed design.
